UNITED STATES PATENT OFFICE.

HARVEY SEWARD, OF PETERSBURG, VIRGINIA, ASSIGNOR TO SEWARD TRUNK AND BAG COMPANY, OF PETERSBURG, VIRGINIA, A CORPORATION OF VIRGINIA.

WARDROBE-TRUNK.

1,315,870.

Specification of Letters Patent.

Patented Sept. 9, 1919.

Application filed December 28, 1915. Serial No. 69,003.

To all whom it may concern:

Be it known that I, HARVEY SEWARD, a citizen of the United States, residing at Petersburg, in the county of Dinwiddie and State of Virginia, have invented certain new and useful Improvements in Wardrobe-Trunks, of which the following is a specification, reference being had therein to the accompanying drawing.

10 This invention relates to certain new and useful improvements in wardrobe trunks, and is in the nature of an improvement on my Patent #1,135,404, for "wardrobe trunk", granted to me April 13, 1915, the 15 object being to improve the general construction of gate hanger and manner of mounting the same within the hanging compartment of the trunk.

Another object of my invention is to provide 20 a gate hanger which is exceedingly simple and cheap in construction and one in which the parts thereof are so connected that an exceedingly strong and durable hanger is formed.

25 Another object of the invention is to provide novel means for mounting the gate hanger within the hanging compartment of the trunk in such a manner that the same will be supported by the side and end wall 30 of the trunk.

Other and further objects and advantages of the invention will be hereinafter set forth and the novel features thereof defined by the appended claims.

35 In the drawings—

Figure 1, is a front elevation of a portion of a wardrobe trunk showing my improved construction of gate hanger in closed position within the hanging compartment 40 thereof;

Fig. 2, is a horizontal section through the trunk showing the gate hanger in full lines in closed position within the hanging compartment and in dotted lines, swung outwardly therefrom; and

Fig. 3, is a perspective of my improved construction of gate hanger and means for mounting the same, the parts being in position to be assembled.

50 Like numerals of reference refer to like parts in the several figures of the drawings.

In the drawings, 1 indicates the body portion of a wardrobe trunk which is provided with the usual drawers, 2 the cover therefor

which is provided with a hanging compartment 3, said cover portion being pivotally connected to the body portion by hinges in the ordinary manner so as to allow the cover portion to move in respect to the body portion.

The upper ends of the body portion and cover portion are provided with swelled portions so as to prevent the trunk from being placed upon this end when the same is being used or shipped.

Secured within the hanging compartment on the inner face of the side opposite to its connection with the body portion and the inner face of a top portion of the hanging compartment, is an angled L-shaped support 5 which is preferably secured to the trunk by rivets passing through the wall thereof, as clearly shown.

Arranged over the support 5 is a bracket 6 the horizontal portion of which extends 75 inwardly under the top of the hanging compartment and is secured to the top of the trunk by rivets passing therethrough, the portion overlying the angled supporting member 5 being also secured to the side of 80 the trunk by rivets, some of these rivets passing through the support 5 and bracket 6 in such a manner that the support 5 and bracket 6 are securely fastened to the end 85 and side of the trunk.

Some of the rivets employed for fastening the bracket and angled support to the trunk, pass through the braces and perform the double function of holding the support and bracket in position within the trunk and 90 for fastening the reinforcing members on the outer face thereof.

The angled support 5 is arranged within the hanging compartment adjacent the edge thereof and is provided with spaced bearing members 7 and 8 in which is mounted the upper and lower ends of a pintle 9 inclosed by clips 10 and 11, which embrace the pintle, said clips 10 and 11 being secured to the angled support 5 by rivets 95 which pass through suitable openings formed therein and openings formed in the bearings 7 and 8 so as to completely inclose the ends of the pintle.

The pintle is prevented from moving vertically within the bearings 7 and 8 by the flap portions 7', 8'. The pintle 9 is carried by the U-shaped end member 12 of a gate

hanger 13 which is formed of parallel bars 14 connected together at one end by the end member 12 and at its opposite end by a U-shaped connecting member 15.

5 The end member 12 is provided with a substantially circular portion to receive the pintle and a U-shaped portion adapted to embrace the ends of the bars 14 and be secured thereto by rivets passing transversely through the same.

10 The end member 15 is also secured by rivets over the opposite ends of the bars 14 forming the gate hanger and has a length greater than the distance between the bars 15 so as to project outwardly above and below the same. By constructing a gate hanger frame in this manner, an exceedingly strong and rigid frame is formed so as to withstand the strain to which it is subjected, as 20 will be later described.

15 Connected to the parallel bars 14 of the gate hanger 13 are brackets formed of two pieces, the supporting portion 16 of each bracket being formed of a strip of metal bent into substantially U-shape form having ears 16' through which rivets pass for securing the same to the upper bar 14 of the gate hanger, the free end of said supporting portion of the bracket being bent upwardly and 25 apertured to form a stop 17 for limiting the outward movement of the garment hangers 18 mounted thereon.

20 The supporting portion of each bracket is provided with a brace 19 formed of a strip of metal bent into substantially U-shaped form having ears 19' for securing the same to the lower horizontal bar; the upper portion of each brace being contracted and having its walls apertured adapted to align 30 with apertured ears 16' formed on the supporting portion through which a rivet passes for securing the brace portion to the supporting portion of each bracket. By this construction, a two-piece bracket is formed having 35 a horizontal supporting portion forming a support for one end of a garment hanger and by the use of two brackets in connection with the gate hanger, a two-point suspension is formed for the garment hangers so as to prevent the garment hangers from swinging, when garments are placed 45 thereon and to provide novel means for supporting the garment hangers in order to allow the same to be readily placed in position upon the supporting portions of the brackets and be removed therefrom.

50 In order to provide means for locking the gate hanger in closed position within the hanging compartment of the wardrobe trunk after the garments have been placed upon the garment hangers, I provide the end member 15 with a housing 20 in which is pivotally mounted a spring-actuated latch 21 provided with a handle portion 21' extending 55 between the parallel bars of the gate

hanger in such position that the same can be readily manipulated.

5 The spring-actuated latch co-operates with a catch 22 secured to the inner face of the opposite wall of the hanging compartment, 70 said catch being formed of a strip of metal bent to form a keeper portion having inclined guide-ways for guiding the latch into the keeper portion when the gate hanger is moved into closed position.

75 From the foregoing description, it will be seen that I provide a pivoted hanger for a wardrobe trunk in which the frame is formed of parallel bars connected together by end pieces, one end piece carrying a pivoted latch and the opposite end piece, a pintle for supporting the frame in such a manner that the same can be readily swung outwardly as shown in dotted lines or inwardly into closed position within the hanging compartment of the trunk, novel supporting means being provided within the hanging compartment for supporting the bearings for the pintle so as to place the strain of the gate hanger upon the side and 80 end of the trunk.

85 It will also be seen that I have provided novel means for mounting the gate hanger to withstand the strain to which it is subjected by providing an angled support, one 90 arm of which is connected to the end of the trunk and the other to the side, and over which is arranged a bracket so as to so connect the support for the gate hanger to the body of the trunk, that the same will be 95 supported from two points and by connecting the bracket and support to the trunk by rivets which pass through the body thereof and are connected to the reinforcing members of the trunk, the gate hanger will be 100 supported so that the same will not sag when the garment hangers carried thereby, are 105 full of clothes.

110 I claim:

1. A wardrobe trunk, composed of two sections pivotally connected together, one section having a hanging compartment, an angled support L-shaped in cross section having one of its sides secured to the end and side wall of said hanging compartment, a bracket arranged over said support at right angles thereto and secured to the end and side wall of said compartment, said support having a bearing secured to the other side thereof, and a gate hanger provided with a 115 pintle mounted in said bearings.

120 2. In a wardrobe trunk, the combination with a hanging compartment, of an angled support L-shaped in cross section having one of its sides secured to the end and top wall of said compartment, spaced bearings secured to said support, and a gate-hanger pivotally mounted in said bearings.

125 3. In a wardrobe trunk, the combination with the hanging compartment thereof, of 130

an angled support L-shaped in cross section secured to the wall thereof, a bracket secured over said support to the walls thereof and at right angles thereto, spaced bearings carried by one of the sides of said support, and a gate hanger having a pintle mounted in said bearings.

4. In a wardrobe trunk, a support for gate-hangers, comprising a bracket, and an L-shaped support arranged upon one another on the inner face of the hanging compartment of said trunk and at right angles to one another, said bracket and support being secured to the top and end walls thereof by rivets passing transversely through said support and bracket.

5. A gate-hanger for wardrobe trunks, comprising a pair of parallel bars connected together by end members, said end members being substantially U-shaped in cross section to receive the ends of said bars, brackets extending laterally from said hanger, and a pintle secured in one of said end members.

6. A gate-hanger, comprising a frame formed of parallel bars connected together by end members, spaced two-piece brackets connected to said bars, said brackets comprising a supporting portion connected to the top bar, and a brace connecting said supporting portion to the lower bar, said sup-

porting portion being provided with an upturned end.

7. A gate-hanger, comprising a frame formed of parallel bars and end members, said end members being substantially U-³⁵ shaped in cross section to receive the ends of said bars, spaced brackets connected to said bars, each of said brackets comprising a supporting portion having an upturned end, and a brace connecting said supporting por-⁴⁰ tion to the lower bar of said frame.

8. In a wardrobe trunk, the combination with the hanging compartment thereof, of a support secured to the side and inner face of the top within the hanging compartment,⁴⁵ said support being provided with two-piece bearings, a gate-hanger provided with spaced parallel supports, a pintle carried by said hanger mounted in said bearings, a catch secured within the hanging compartment to the opposite side from the support, and a pivoted latch carried by the gate-hanger coöperating with said catch.

In testimony whereof I hereunto affix my signature in the presence of two witnesses.⁵⁵

HARVEY SEWARD.
